CATCH

Earl Borchers, Rockford, Ill., assignor to American Cabinet Hardware Corporation, Rockford, Illinois, Rockford, Ill., a corporation of Illinois

Application February 20, 1942, Serial No. 431,631

16 Claims. (Cl. 292—18)

This application is a continuation in part of my pending application, Serial No. 398,918, filed June 20, 1941.

The invention relates generally to catches and more particularly to a catch for use in holding the door of a cabinet such as a kitchen cabinet or the like.

The general object of the invention is to provide a novel catch having relatively few parts of simple construction and requiring a minimum of labor to assemble.

Another object is to provide a novel catch which effectively holds the strike, which is easy acting, and which may be readily mounted in the cabinet.

A further object is to provide a novel catch having a pair of strike-receiving jaws which exert an equal pressure on the strike and which may operate properly with such equalized pressure even though the strike be somewhat misaligned with the catch.

Still another object is to provide a novel catch the jaws of which may move independently of each other to enable them to operate with a misaligned strike, said jaws being spring-operated and so arranged that the spring is under an initial tension prior to the entrance of the strike.

A still further object is to provide a catch of the foregoing general character, the base structure of which may be varied to adapt the catch for different ways of mounting it or for cabinets made either of wood or sheet metal.

It is also an object to provide a catch of the foregoing general character, which may have the strike-receiving portions formed either for a strike movable longitudinally of the jaws or transversely of the jaws.

Other objects and advantages will become apparent from the following description taken in connection with the accompanying drawings, in which:

Figure 1 is a fragmentary perspective view of a cabinet provided with a catch embodying the features of the invention.

Fig. 2 is a horizontal sectional view of the catch and showing the strike in engaged position.

Fig. 3 is a view similar to Fig. 2 but showing the strike partially withdrawn.

Fig. 4 is a sectional view taken on the line 4—4 of Fig. 2.

Fig. 5 is a perspective view showing the parts disassembled.

Fig. 6 is a perspective view of a modified form of catch mounted in a sheet metal cabinet.

Fig. 7 is a sectional view of the catch and cabinet shown in Fig. 6.

Fig. 8 is a perspective view showing the catch ready for assembly in the cabinet.

Fig. 9 is a view partially in section of another modified form of catch and showing the manner of mounting it in a cabinet.

Fig. 10 is a sectional view taken on the line 10—10 of Fig. 9.

Fig. 11 is a perspective view of a strike used with the catch shown in Figs. 9 and 10.

As mentioned above, the catch is designed for use with cabinets such as kitchen cabinets. All forms of the catch comprise generally a pair of jaws relatively movable toward and from each other, between which the strike is adapted to enter. The jaws are supported so as to extend from a generally rectangular or box-like housing provided with means for securing the catch to the desired part of the cabinet. The jaws are independent of each other and are pivotally supported by being shaped to fit over an integral portion of the housing for pivotal movement. To hold the jaws in place, a spring is located within the housing and bears against the respective jaws, said spring also having the function of resiliently resisting movement of the jaws by engagement with the strike. The assembly of the parts is thus greatly simplified in that no riveting is required, and also the number of parts is reduced since the spring serves the double function of holding the jaws on their pivotal support and providing resilient action of the jaws when engaged by the strike.

For purposes of illustration, the preferred form of catch is shown in Figs. 1 to 5 of the drawings as being mounted on a shelf or base 10 of a wood cabinet having a side wall 11, a door frame 12, and a door 13 hinged thereto. The catch is adapted to be mounted adjacent the front edge of the shelf and a cooperating strike, indicated generally at 14, is mounted on the inner face of the door in alignment with the catch.

The catch comprises a base in the form of a box-like housing 15 generally rectangular in form and herein providing side walls 16, a top wall 11 integral therewith and a rear wall 18 bent downwardly from the top wall and positioned between the two side walls. For mounting the catch in the cabinet, a pair of ears 20 integral with the side walls 16 extend laterally therefrom to rest flatwise on the shelf 10. The ears are provided with slots 21 for screws 22 by which the catch may be secured in place. Preferably the slots 21 are elongated so that the catch may be adjusted

to proper position relative to the strike after the screws 22 are partially inserted and before they are tightened.

Mounted within the box-like housing 15 and extending forwardly therefrom is a pair of jaws each indicated generally at 23. Each jaw comprises a strip of metal bent on transverse lines in its forwardly extending portion to guide the strike therebetween and retain it when the door 13 is closed, the strike in this case being movable longitudinally of the jaws. To this end each jaw has a U-shaped portion 24 (see Fig. 5) with its forward edge outwardly flared as at 26. The strike is preferably made of a strip of metal having an intermediate portion bent to provide a large V-shaped head 27 and a shank portion 28 extending from outwardly turned ears 29 adapted to be secured to the inner facing of the door as by screws 30. The outwardly flared ends of the jaws guide the head 27 and when the head is fully inserted between the jaws, the latter grip the shank 28 in back of the head 27.

The jaws 23 are mounted for pivotal movement during the passage of the strike in and out of locking position, and one of the principal features of the invention resides in the simple manner in which the jaws are so supported. To this end, the side walls 16 of the box-like housing are provided with integral lugs 32 at their front edges, bent toward each other so that they are positioned in end-to-end but spaced relation (see Figs. 4 and 5). The lugs 32 thus provide opposite edges or marginal portions and the jaws 23 are shaped to fit over such edges and to be retained in abutting relation therewith by spring means mounted within the box-like housing. In the preferred form, the jaws are bent on transverse lines intermediate their ends to provide grooves 33 in which the edges of the lugs 32 are located. To hold the jaws against shifting movement relative to the edges of the lugs 32, the grooved portion of each jaw is centrally apertured as at 34 to fit over tongues 35 extending from the edges of the lugs 32 into the intervening space.

With the foregoing construction, the jaws are assembled into the box-like housing by inserting them in the space between the tongues 35 and then moving them laterally to insert the tongues into the apertures 34 and to position the grooves 33 over the edges of the lugs 32. To hold the jaws in such position, as mentioned above, a spring is mounted within the housing tending to separate the jaws. In its preferred form the spring, indicated at 40, is a compression spring of barrel-like form and is mounted between and bears against the inner ends of the jaws. To hold the spring in position and prevent it from slipping off the jaws, each jaw is provided with an indentation or boss 41 over which the end of the spring fits. The spring 40 thus presses the inner ends of the jaws flatwise again stops formed by the side walls 16 and holds the jaws in position on the edges of the lugs 32. The spring 40 also serves to resist separating movement of the jaws by the strike.

In operating the device, when the door is being closed, the head 27 of the strike engages the outwardly flared ends 26 of the jaws and, because of their slant, the strike forces the jaws apart, thereby compressing the spring 40. The maximum separation of the jaws occurs when the enlarged portion of the head 27 is entering between the jaws, as illustrated in Fig. 3. After the enlarged portion of the head 27 passes in between the U-shaped portions 24 of the jaws, the

spring 40 causes the jaws to snap back into contact with the shank 28 of the strike. The spring thus holds the jaws firmly in contact with the shank 28, as shown in Fig. 2.

When the door 13 is pulled open, the head 27 of the strike again spreads the jaws until the head is completely removed from the jaws. The spring 40 thereupon causes the inner ends of the jaws to be spread until they are in flatwise abutment with the side walls 16 of the box-like housing. When so positioned, the forward end of the jaws are slightly spaced to permit easy entrance of the strike, and the spring is under an initial tension.

Should the strike be slightly misaligned with the jaws, the head 27 of the strike will cause one of the jaws to move before the other. Such movement is permitted in view of the fact that the jaws are independently supported. However, the pressure on the two jaws is equalized by virtue of the fact that the spring bears solely on the jaws and the pressure on one is equal and opposite to the pressure on the other. Thus the jaws will exert the same holding pressure on a slightly misaligned strike as they will on a strike accurately centered with respect to the jaws.

The assembly of the various parts of the catch is such that very little labor is required. The two jaws are first inserted in the space between the tongues 35 and are then moved laterally so that the tongues 35 are inserted into the apertures 34 of the jaws and the grooves 33 of the jaws rest against the edges of lugs 32 on the front wall of the housing. The bottom of the housing is open so that the spring may then be inserted therein and positioned between the jaws with its end seated over the bosses 41. The spring 40, by its spreading action on the jaws, holds them in pivotal engagement with the edges of the lugs 32 and on the tongues 35. The spring thus has the double function of retaining the jaws in place in the housing, as well as to resist separating movement of the front portions of the jaws by the strike.

In the modified form of catch shown in Figs. 6, 7, and 8, the shape of the jaws and the manner of supporting them in the base structure is the same as in the case of the preferred form. The base structure, however, differs and is so constructed as to permit the catch to be readily assembled in a sheet metal cabinet. As shown herein, the sheet metal cabinet comprises a hollow wall 50 having a front edge flange 51. A sheet metal door, indicated at 52, is shaped to overlie the front edge flange 51. This form of cabinet is merely illustrated as typical, but the invention is not limited to use only with such form of cabinet.

The base structure is formed to be mounted within the wall 50 and to be supported by and attached to the front edge flange 51. The base structure is preferably made of one piece of metal and comprises a base piece or flange 53 adapted to be mounted on the front face of the edge flange 51 of the wall. The base piece 53 is provided with a central aperture 54 to permit a strike to extend therethrough. To secure the catch to the wall the base piece may also be provided with a pair of holes 55 through which screws may extend for threading into apertures 56 formed in the wall flange 51.

Extending inwardly from the base piece 53 is an extension 57 having formed at its inner end a box-like structure 58 to support the strike-receiving jaws. In the present instance such box-

like structure comprises side walls 60 and a rear wall 61. The side walls 60, as in the catch of the preferred form of construction, are provided with lugs 32 each having a tongue 33 to support the jaws in the same manner as in the preferred form. Since the box-like portion 58 in this form is not mounted against a flat face of the cabinet structure, the side walls 60 are provided with lugs 62 bent inwardly over the jaws 23 to prevent them from being dislodged by accident and serving to guide the jaws and hold them against turning movement on axes parallel to the spring 40. To permit the catch to be inserted into the interior of the wall 50, the front edge flange 51 is provided with an aperture 63 of sufficient size to permit the box-like structure 58 to pass therethrough.

The strike, indicated at 64, utilized with this form of catch is preferably of rounded form rather than being bent from a strip, and is provided with a stud 65 secured in the door 52 as by threading it into an aperture therein.

The modified form of catch shown in Figs. 9, 10, and 11 is adapted to be mounted in a cabinet in such a manner that the strike and jaws move laterally relative to each other. Thus the catch may be mounted on the inside of a door 70 while the strike is mounted on the adjacent frame 71. In this form of catch, the base structure is substantially the same as the base structure shown in the preferred form, but the attaching ears, here indicated at 72, may, if desired, be reduced in size.

Since the catch is designed for a strike which moves transversely of the jaws, that is, a strike which enters the jaws from the sides thereof instead of from the ends, the outer or strike-receiving portions of the jaws are formed so that they may readily be spread by such transverse movement. Thus the outer ends of the jaws, here indicated at 73, are bent a short distance along a line extending longitudinally of the jaws to provide a V-shape in cross section, as illustrated in Fig. 10. The V-shape form provides outwardly flared portions so that the strike in entering therebetween will force the jaws apart to permit it to pass between the jaws. When the door of the cabinet is fully closed, the jaw-receiving portion of the strike lies between two jaws and in the space between the jaws and the rear surface of the door.

The strike in its preferred form, as illustrated in Fig. 11, comprises a flange 74 adapted to be secured to the adjacent edge surface of the wall 71. The flange 74 is provided with an integral portion extending perpendicularly from the edge of the wall and rounded into a cylindrical portion 75.

From the foregoing, it is apparent that I have provided a novel catch having relatively few parts, which parts are of simple construction and require a minimum of labor to assemble. The catch may be readily mounted in the cabinet and effectively holds the strike when the two are engaged. The jaws are so mounted in the box-like housing that they exert an equal pressure on the strike whether the strike be exactly centered with the catch or whether it be slightly misaligned. The spring serves both to resiliently hold the jaws in engagement with the strike and also to hold the jaws in place in the housing, the spring being under an initial tension due to the fact that it holds the inner ends of the jaws flatwise against the side walls of the housing.

It will also be evident from the foregoing de-

scription that I have provided a catch, the base structure of which may be varied so that the catch may be mounted in different ways on either cabinets made of wood or sheet metal. Also, the jaws of the catch may be so formed that the strike may be received by movement either longitudinally of the jaws or transversely of the jaws.

I claim as my invention:

1. A catch comprising, in combination, a base having a box-like portion open at its front face, said box-like portion being provided with lugs in said front face extending toward each other, a pair of jaws extending into said box-like portion and pivotally supported by said lugs, and spring means within said box-like portion bearing against said jaws.
2. A catch comprising, in combination, a base having a box-like portion having at its front face a pair of lugs extending edgewise toward each other, a pair of jaws each comprising a strip of metal bent to form a U fitting over the edge of one of the lugs, and spring means within the box-like portion mounted between and bearing against the jaws, and jaws thereby being pivotally supported by the edges of said lugs.
3. A catch comprising, in combination, a base having a box-like portion including side walls having lugs at their forward edges bent toward each other, a pair of jaws bent to provide grooves fitting the opposed edges of said lugs whereby said jaws are pivotally supported, and a spring mounted within said box-like portion and tending to separate the inner portions of said jaws.
4. A catch comprising, in combination, a base including a box-like portion having side walls provided with lugs extending toward but spaced from each other, each of said lugs having a tongue extending into the intervening space, a pair of jaws each bent to provide a grooved portion bearing against the edge of the lug and having an aperture fitting over the tongue, and spring means mounted within the box-like portion and tending to separate the inner ends of the jaws.
5. A catch comprising, in combination, a base having a box-like portion having an opening at its front face and provided with a pair of tongues extending laterally toward each other in said opening, a pair of jaws extending through said opening having apertures fitting over the tongues, and spring means within the box-like portion bearing against the respective jaws.
6. A catch comprising, in combination, a base comprising a pair of spaced ears connected with an integral box-like portion comprising side, top and rear walls, said side walls at their front edge being provided with lugs bent toward each other, a pair of jaws pivotally supported by the edges of said lugs, and spring means within the box-like portion and bearing against said jaws.
7. A catch comprising, in combination, a base including a pair of lugs in end-to-end relation but longitudinally spaced, a pair of jaws bent at an intermediate point to provide grooves fitting over the adjacent end edges of said lugs, the portions of said jaws in front of said lugs being shaped to receive a strike, and a spring located between and bearing against the rear portions of said jaws.
8. A catch comprising, in combination, a base including a pair of lugs in end-to-end but longitudinally spaced relation, a pair of tongues extending from the respective lugs into the intervening space, a pair of jaws apertured at an in-

termediate point to fit over the respective tongues and bearing against the edges of the respective lugs, the portions of said jaws in front of said lugs being shaped to receive a strike, and a spring located between and bearing against the rear portions of said jaws.

9. A catch of the character described comprising, in combination, a base comprising a box-like structure having a top wall, side walls and a rear wall bent downwardly from the top wall, ears bent laterally from the lower edges of the side walls and adapted to be mounted on a fixed part of the cabinet, said side walls at their front edges being provided with lugs bent toward each other, a pair of jaws comprising strips of metal bent on transverse lines to fit over the adjacent edges of said lugs and thereby be pivotally supported, and spring means within the box-like structure and bearing against said jaws, the front portion of said jaw being bent on transverse lines to receive a strike movable longitudinally of the jaws.

10. A catch for a sheet metal cabinet having a hollow wall comprising, in combination, a base adapted to be secured to the front of the edge face of the wall and provided with a central aperture to permit a strike to pass therethrough, an extension projecting from said base through the edge face of the wall and provided with a box-like portion on its inner end, a pair of jaws pivotally supported in said box-like portion and adapted to receive a strike passing through the aperture in the base, and spring means within the box-like portion to resist spreading of the jaws by the strike.

11. A catch for a sheet metal cabinet having a hollow wall comprising, in combination, a base adapted to be secured to the front edge face of the wall and provided with an aperture for passage of a strike therethrough, an extension projecting rearwardly from the base through the front edge of the wall and into the interior thereof, a box-like structure formed on the inner end of said extension and provided at its front with a pair of laterally spaced lugs, a pair of jaws pivotally supported by the edges of said lugs and having strike-receiving portions at their front ends, and spring means within the box-like portion and tending to spread the rear portion of the jaws to resist separation of the strike-receiving portions.

12. A catch comprising, in combination, a base structure including a box-like portion having an opening in one wall, a pair of jaws extending through said opening and pivotally supported by the marginal portions of said wall at said opening, and spring means mounted within the box-like portion and bearing against said jaws, said jaws extending beyond said box-like portion and being bent along longitudinal lines to receive a strike movable transversely thereof.

13. A catch comprising, in combination, a base including a housing having an opening in one wall, a pair of jaws bent along transverse lines at their intermediate portion to fit over the marginal portions of said wall at said opening and thereby be pivotally supported, and spring means mounted between the portions of said jaws with-

in the housing, the portions of said jaws extending beyond the housing being bent along longitudinal lines to receive a strike movable transversely of the jaws.

14. A catch comprising, in combination, a pair of elongated pivotal jaws each formed from a flat strip of metal and having an outer strike-engaging portion, an inner end portion and an intermediate bearing portion, a supporting structure also formed of sheet metal and providing fixed opposed bearing elements for coaction with said intermediate bearing portions of the jaws and stops offset inwardly from said fixed bearing elements, and a spring interposed between the inner end portions of the jaws and acting to press such ends in opposite directions against said stops with the jaws substantially parallel, said bearing portions on the two jaws interfitting with their respective fixed bearing elements so as to prevent endwise movement of the jaws when engaged by a strike and being disengageable from their respective bearing elements by forcing the jaws together against the action of said spring.

15. A catch comprising, in combination, a pair of elongated pivotal jaws each formed from a flat strip of sheet metal and having an outer strike engaging portion, an inner end portion and an intermediate bearing portion, a supporting structure also made of sheet metal and providing fixed opposed bearing elements for coaction with said intermediate bearing portions of the jaws and stops offset inwardly from said fixed bearing elements, and a coiled compression spring interposed between the inner end portions of the jaws and acting to press them in opposite directions against said stops with the jaws substantially parallel, said bearing portions of the two jaws interfitting with their respective bearing elements to positively prevent shifting of the jaws relative to said bearing elements and being disengageable from their respective bearing elements by forcing the jaws together against the action of said spring.

16. A catch comprising, in combination, a sheet metal base structure having two spaced supporting members providing fixed opposed bearing elements, a pair of sheet metal jaws having intermediate their ends bearing portions adapted to interengage with said bearing elements while permitting the jaws to turn on said elements as fulcrums, said jaws having strike-engaging portions at their outer ends and inner end portions engageable with said supporting members inwardly of the bearing elements, a coiled compression spring interposed between said inner end portions of the jaws to hold them in spaced substantially parallel relation with said inner end portions pressed against said supporting members, and means on said members coacting with the jaws to hold them positively against pivotal movement on axes parallel to the axis of said spring, said jaws being disengageable from their respective bearing elements by forcing them together against the action of said spring.

EARL BORCHERS.
